United States Patent Office.

ABRAHAM LANG, OF BUFFALO, NEW YORK.

Letters Patent No. 98,074, dated December 21, 1869.

IMPROVEMENT IN DEVICES FOR PREVENTING LEAKAGE ABOUT CHIMNEYS.

The Schedule referred to in these Letters Patent and making part of the same.

I, ABRAHAM LANG, of Buffalo, in the county of Erie, and the State of New York, have invented certain Improvements in Roof-Leakage Preventives, of which the following is a specification.

The nature of my invention consists in protecting the roof of a house, and guarding the same against leakages caused by imperfect joints of the roof and chimney. I refer to the drawing, which makes part of this specification, and which illustrates my invention more fully.

Letter A, in the same, represents a chimney, provided with a wood frame or box, B. The same is surrounding the chimney near the roof, and resting on the same. The space between the chimney and frame or box B is filled with cement.

It will be observed, that if the frame B, as well as the cement enclosed by the same, is extending or projecting sufficiently over the roof, and a gutter or gutters are so secured to the roof and the chimney, that the same will terminate in the case or cement surrounding the chimney, leakages around the sides of the chimney will be impossible.

It will also be observed, that in order to carry out my invention, it is not necessary to enclose the cement surrounding the chimney in a frame, B, but that the same may be removed as soon as the cement has set. It can be readily seen that my invention is applicable either to new or old chimneys; that no particular construction of chimney is required, to make use of my invention; and, that there can be no doubt but this invention will be received by the public most favorably, and that a great deal of annoyance will be avoided.

C and D show a mere modification of B. It represents the cement protection without the frame.

Having thus fully described my invention, What I desire to secure by Letters Patent, is—

The combination of the adjustable box B, with the cement surrounding the chimney, constructed and arranged as described, and for the uses set forth.

ABRAHAM LANG.
